UNITED STATES PATENT OFFICE

96,708

DESIGN FOR A PICTURE FRAME

Geza Stephan, Chicago, Ill.

Application June 20, 1935, Serial No. 57,343

Term of patent 7 years

To all whom it may concern:

Be it known that I, Geza Stephan, a citizen of the United States and resident of Chicago, in the county of Cook and State of Illinois, have invented a new, original, and ornamental Design for a Picture Frame, of which the following is a specification, reference being had to the accompanying drawing, forming a part thereof.

My design is characterized by an ornamental star shaped frame joined at its interior apexes by an ornamented circular frame; ornamental rosettes covering the points of contact of the frame and circle.

I claim:

The ornamental design for a picture frame as shown and described.

GEZA STEPHAN.
